UNITED STATES PATENT OFFICE.

JOHN A. AUE, OF FREEPORT, ILLINOIS, ASSIGNOR TO HARRISON WOODMANSE, OF FREEPORT, ILLINOIS.

TIGHTENER FOR BRACE-RODS.

No. 802,547.

Specification of Letters Patent.

Patented Oct. 24, 1905.

Application filed July 18, 1905. Serial No. 270,303.

To all whom it may concern:

Be it known that I, JOHN A. AUE, a citizen of the United States of America, residing at Freeport, in the county of Stephenson and 5 State of Illinois, have invented certain new and useful Improvements in Tighteners for Brace-Rods, of which the following is a specification.

The object of this invention is to provide 10 means for tightening diagonal brace-rods—as, for instance, the crossed brace-rods in windmill-towers, to which this invention particularly relates.

In the accompanying drawings, Figure 1 is 15 a side elevation of a section of a windmill-tower having the brace-rods thereon tightened by means of my improvement. Fig. 2 is an enlarged section, at the dotted line 2 2 in Fig. 1, of parts there shown. Fig. 3 is a 20 full-sized isometrical detail view of the clamp-body of the tightener.

Like letters of reference indicate corresponding parts throughout the several views.

A represents angle-iron corner-posts of a 25 windmill-tower. B represents angle-iron cross-girths securely connecting them together.

C represents crossed brace-rods (attached at 30 their opposite ends by means of bolts or rivets D to the adjacent and opposite corner-posts A) drawn tensely by applying force to their middle portions and forcing them in opposite directions in a plane parallel to their points of attachment D.

E is the clamp-body of a tightener having 35 a substantially X-shaped recess E' therein to admit a brace-rod C, placed obliquely thereinto and provided with an upwardly-extending lug E² to engage the downwardly-projecting member F of an angle-iron cross-girth B.

G is a J-bolt engaging the free edge of the outwardly-projecting member H of such cross-girth B and extending through a transverse hole I in the clamp-body E.

J is a nut applied to the threaded straight shank K of the J-bolt G to secure the brace-rod C into the recess E' in the clamp-body E.

After the parts of the tightener have been

put together in the manner already described the brace-rods C are forced simultaneously 50 in opposite directions until they are as tense as is desired and are then secured in such tense condition to the contiguous cross-girth B. They may be forced inward with identically the same results. Obviously whenever 55 it is desired at any time to retighten any or all of the brace-rods C it can be done with ease and despatch.

Having fully described my invention, what I claim as new, and desire to secure by Letters 60 Patent, is—

1. In a tightener for brace-rods, in combination, a clamp-body having a substantially X-shaped recess therein to admit a brace-rod—placed obliquely thereinto—and provided with 65 an upwardly-extending lug to engage the downwardly-projecting member of an angle-iron cross-girth, a J-bolt engaging the free edge of the outwardly-projecting member of such cross-girth and extending through a 70 transverse hole in the clamp-body and a nut applied to the threaded straight shank of the J-bolt to secure a brace-rod into the recess in the clamp-body and the latter to such cross-girth, substantially as described. 75

2. In a tightener for brace-rods, in combination, a clamp-body E, having a substantially X-shaped recess E' therein to admit a brace-rod, as C—placed obliquely thereinto—and provided with an upwardly-extending lug E² to engage the member F of an angle-iron cross-girth, a J-bolt G engaging the free edge of the outwardly-projecting member H of such cross-girth and extending through a 80 transverse hole I in the clamp-body E, and a nut J applied to the J-bolt to secure a brace-rod, as C, into the recess E' in the clamp-body E and the latter to such cross-girth, substantially as described. 85

In testimony whereof I have signed my name 90 to this specification in the presence of two subscribing witnesses.

JOHN A. AUE.
